[57] CLAIM

The ornamental design for a slide, as shown and described.

DESCRIPTION

FIG. 1 is a front elevational view of a slide showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a top perspective view thereof;

FIG. 8 is a front elevational view of a second embodiment of the slide of FIG. 1;

FIG. 9 is a rear elevational view of FIG. 8;

FIG. 10 is a top plan view of FIG. 8;

FIG. 11 is a bottom plan view of FIG. 8;

FIG. 12 is a right side elevational view of FIG. 8;

FIG. 13 is a left side elevational view of FIG. 8; and,

FIG. 14 is a top perspective view of FIG. 8.

The broken line disclosure of FIGS. 1-3, 5-10 and 12-14 is for illustrative purposes only and forms no part of the claimed design.
